UNITED STATES PATENT OFFICE.

ALPHEUS FAY, OF LOUISVILLE, KENTUCKY.

CREAM-SEPARATOR AND CHURN.

1,057,335.

Specification of Letters Patent. Patented Mar. 25, 1913.

Application filed February 18, 1911. Serial No. 609,454.

To all whom it may concern:

Be it known that I, ALPHEUS FAY, a citizen of the United States, residing at Louisville, in the county of Jefferson and State of Kentucky, have invented a certain new and useful Cream-Separator and Churn, of which the following is a specification.

The object of my invention is to provide improved means for successively separating the cream from milk and then churning the cream to extract the butter, by a combined mechanical and aerating treatment.

My invention also has for its object the performance of other processes in connection with the treatment of cream, milk or butter, where a mechanical agitation or aeration or both may be necessary or desirable.

The processes to which my invention is most applicable will hereinafter be more fully set forth.

My invention consists in the provision of a novel arrangement of driving mechanism, and the combination therewith of a peculiar form of agitators for imparting a centrifugal movement to the liquid, as well as a peculiar positioning of the agitators whereby the induction of currents in the liquid is facilitated.

My invention also consists in the details of construction and arrangement hereinafter more fully described and claimed.

The drawing forming part of this specification illustrates an embodiment of my invention, being a vertical elevation of same, with the vessel and the gears, as well as one of the agitators, shown in section.

In this illustration the two agitators 1 are of such design as to produce a centrifugal impelling effect on the liquid, as will be described, and each is mounted on a shaft 2, which shafts are journaled at 2' in the bracket 3 that extends across the top of the vessel 4, and is suitably clamped thereto, as will be more fully described. Above their bearings in the bracket the shafts have bevel pinions 2^a secured to them, and bear in additional bearings 2^{''} above the pinions. One of the bevel gears 2^a is in mesh with a bevel gear 5, and the other one is in mesh with a bevel gear 5', both of which are mounted to rotate in vertical planes loosely on a horizontal driving shaft 5^a, that has bearings 5^a

in the bracket 3, flanking the pinions 2^a. The agitators 1 are adjustable on the shafts 2, and in operation are adjusted so that they are in juxtaposition, and thereby act upon the liquid as brakes to each other, to increase the agitating effect.

A driving gear 5^b is rigidly mounted on the shaft 5^a between the bevel gears 5 and 5'. The bevel gear 5 has a stud 5^c rigidly mounted thereon parallel to the shaft 5^a, and the differential gear 5^d comprising a member 5^{d'} and a member 5^{d''} is loosely mounted on this stud 5^c, with its member 5^{d'} in mesh with the gear 5^b, planetary thereto. The other bevel gear 5' has a gear 5^e rigidly mounted on it, coaxial with it, and in mesh with the other member 5^{d''} of the differential gear 5^d, and is of diameter equal therewith. As shown, the gear 5^b is of twice the diameter of the member 5^{d'} of the gear 5^a, with which it meshes. Variations of the proportions of these gears may occur, however, it being essential, of course, that the aggregate diameters of the meshing gears be equal, in any case.

From the foregoing description it is evident that the only operative connection between either of the gears 5 and 5' and the shaft 5^a is through the medium of the gear 5^b, the differential gear 5^d and its stud 5^c to the gear 5, and through the intermeshing relation between the differential gear 5^d and the gear 5^e to the gear 5'. This connection thus constituted operates in such a manner that if the resistances imposed upon both gears 5 and 5' be equal, they will be rotated both at the same speed under the influence of the shaft 5^a, but if the resistance on either of them varies from that on the other, the one encountering the less resistance will rotate faster than the other, in exact inverse proportion to the resistances on the two gears. Since the two agitators are driven independently except through this connection, it will be seen that this correlation exists between the agitators also. It will also be seen that by virtue of this arrangement each of the agitators 1 provides the reaction for the action in driving the other agitator, so that increased resistance on one agitator, with consequent reduction in speed thereof must result in increased speed of the other agitator. If the resistances encountered by

this other agitator remain the same during the time of increased resistance imposed on the first mentioned agitator, an increase in total energy applied to the machine will be necessary, but the increase will not be as high in proportion to the increased work performed as in a machine with a stationary reactive member and a single moving operative member, as has been the common practice.

Each of the agitators 1 comprises, as shown, a series of superposed rigidly assembled impelling members 1', secured to the lower open end of a tubular shaft 1^a, which, in turn, is held in a hub 1^b at its upper open end, the hub 1^b being of open construction to admit atmospheric air to the tubular shaft. This open upper end of said tubular shaft is approximately even with the upper rim of the vessel 4, and to accommodate the hub 1^b in proper position relative to the top of the vessel 4, the bracket 3 has an upwardly arched formation, as illustrated. It will also be seen that in order to have the two agitators at the same height in the vessel, with their impellers opposite, and at the same time preserve the proper proportion between said agitators and their driving mechanism, above described, the shafts 2, and consequently, the agitators thereon, are made to converge upwardly to a material extent. This inclination of the agitators has a beneficial effect on the operation of the apparatus, in that the centrifugally projected currents of liquid acquire an upward tendency laterally outward in the vessel, inducing well defined currents in the body of the liquid, and facilitating the distribution of the agitating and aerating action of the apparatus to all of the liquid being operated upon therein.

Each of the members 1' of the impeller consists in a series of radial channels of outwardly increasing triangular cross section joined by plane web parts, and are advantageously formed of sheet metal; their general contour is circular. The plurality of members 1', thus formed, are secured together so that each succeeding one in the series has the outer part of its channel secured to the plane web of the preceding, and its plane webs secured to the outer parts of the channels of the one succeeding it, as is instanced by the intermediate member of each impeller illustrated, where there are only three members to the series in each impeller. These members are thus secured together by clips 1'' embracing the adjacent parts of each, across their peripheries, and riveted through them. This adds strength to the assembled impeller. The lowermost member has an opening to fit the shaft 2, while the others have openings of diameter approximating that of the interior of the tubular

shaft 1^a and aligned therewith. The uppermost impeller is attached to the lower part of said tubular shaft 1^a by a collar 1^{a'}, of angular crosssection, having one leg attached to the impeller member and the other to the tubular shaft and fitting snugly therearound. The hub 1^b is secured on the shaft 2 by a set screw 1^{b'} and has a series of downwardly diverging arms 1^{b''} having their lower ends connected by a ring 1^{b'''}, which fits snugly around and is attached to the tubular shaft substantially flush with its upper open end; this allows the open mounting of the tubular shaft, as above alluded to. The shafts 2 extend to the bottom of the vessel and their lower ends have suitable step bearings 2''', as shown. This steadies the shafts, and the fitting of the lowermost member of the impeller to the shaft, steadies the impellers on the shafts. The hub 1^b and the collar 1^{a'} may be of cast metal and both may be of integral formation, including, in the case of the hub, its ring 1^{b'''}.

The bracket 3 is formed integral, including the lower and upper bearings for the shafts 2, the flanking bearings for the shaft 5^a and the arched main part with its vessel-engaging and clamping means. At one side this clamp comprises a downward and in-turned lug 3', integral with the bracket, and at the other side a simple boss corresponds in position and has an opening admitting the upward passage of the straight threaded part of an inturned hook bolt receiving a thumb-nut 3'', by which the entire bracket may be tightened on the vessel. Ears 4' are secured to the vessel near its rim, outside, for the lug and the hook bolt to engage under. The vessel has an outlet 4^a, suitably controlled, and a handle 6 is secured to the shaft 5^a at one side for manual operation.

My invention is most advantageously used in the separating and churning above mentioned. In this process, fresh sweet milk is placed in the vessel 4, almost filling it, the agitators 1 being adjusted to their uppermost position, as they are illustrated in the drawing, so that the upper open ends of the tubular shafts 1^a are above the surface of the liquid. The milk is then agitated by the operation of the mechanism, the agitators exerting a centrifugal impelling effect on the milk, as above stated, and setting up currents in the liquid to produce complete circulation throughout the body of liquid, and producing a partial vacuum in the central regions of the impellers by the displacement of the liquid therefrom, which induces a downward circulation of air through the tubular shafts 1^a, which air is readily distributed along with the liquid, throughout the body of liquid, under the centrifugal action, and thoroughly aerating the milk. The milk is preferably introduced into the vessel

at a temperature of from 40 to 50 degrees Fahrenheit, while the air entering the liquid is of atmospheric temperature, or about 60 or 70 degrees Fahrenheit, and of substantially the atmospheric pressure. After the milk has been agitated and aerated in the above manner for a period of from five to ten minutes, the cream will be in proper condition to separate in its entirety, upon which the agitation is discontinued and the liquid allowed to rest for a few minutes, until the separation of the cream from the milk has become complete, and the cream has risen to the top of the vessel. Then the skimmed milk is drawn off through the outlet 4^a, leaving the separated cream in the vessel. By varying the body of skimmed milk drawn off, the cream may be left with any ordinary percentage of butter fat desired. After the desired proportion of skimmed milk has been withdrawn, the agitation is resumed to perform the churning operation, the agitators 1 being lowered to the proper positions on the shafts 2 to properly operate on the reduced quantity of liquid now left in the vessel. The temperature of the cream in the vessel will now have risen to approximately the atmospheric temperature, or to from 60 to 65 degrees Fahrenheit, and the churning agitation is continued at this temperature until the butter is separated from the cream, which will ordinarily require about from three to five minutes of time. The butter may then be removed and worked in the usual manner, and for conveniently removing the butter, the bracket 3 may be readily removed from the vessel along with the agitators 1 on their shafts 2, leaving free access to the vessel and leaving the entire interior of the vessel smooth and with an entire absence of projections or crevices, facilitating a thorough removal of the butter and permitting a thorough cleansing of the interior of the vessel after the residue from the churning has been withdrawn through the outlet 4^a. If desired, the skimmed milk that was previously withdrawn may be now added to the residue from churning before withdrawal thereof, and the agitators 1 be again introduced into the liquids in the vessel and operated to thoroughly mix them, resulting in the production of a good serviceable fresh sweet milk, which contains all the natural solids of the milk except the butter fats, and which has the natural flavors of the fresh whole milk.

A poor quality of butter may be operated upon, to improve it, by the use of my invention, placing such butter in a suitable amount of pure water in the vessel and agitating it and aerating it in the manner above described in connection with the account of the separating and churning operations, and at a temperature of 50 or 60 degrees

Fahrenheit. Thus the butter may be granulated, permitting a most efficient purifying action of the air thereon and of the water in the vessel, which may be withdrawn and fresh water introduced, as may be required, the entire operation resulting in producing the butter granules in a neutral state, with their impurities eliminated. These neutral granules may then be removed and salted and worked and otherwise treated according to good practice in the production of marketable and palatable fresh butter, with which it is identical. Moreover, if desired, these granules may be mixed with sweet milk to produce a high quality of cream of any desired percentage of butter fat, of smooth consistency, thoroughly fresh sweet and pure, and adaptable for all of the uses that good cream is usually employed in. The combined aeration and agitation is an especially desirable feature of all of the operations in the processes herein described.

Other advantageous uses will be suggested in the employment of my invention, and divers minor modifications may occur in its use, and I therefore do not wish to be understood as limiting myself to the precise details of construction and arrangement herein illustrated and described as examples of the embodiment of my invention, but

What I claim as new and desire to secure by Letters Patent is:

1. In a device of the character described, hollow agitators, shafts on which the agitators are mounted and with which they rotate, and driving means for said shafts, the agitators being juxtaposed so that their peripheries do not intersect, and said shafts being inclined from the agitators so that they converge to said driving means. 105
2. In a device of the character described, agitators, shafts with which the agitators rotate, and driving means for said shafts, said agitators being juxtaposed so that their peripheries do not intersect, and said driving means being adapted to drive said agitators non-synchronously. 110
3. In a device of the character described, hollow agitators juxtaposed so that their peripheries do not intersect, shafts with which the agitators rotate, pinions on the shafts, gears meshing with the pinions, a driving shaft, and correlative gearing contained between said gears around said shaft, said gears being separated only sufficient to 115 contain said gearing between them, and said shafts being convergent from said agitators to said gears. 120
4. In a device of the character described, hollow agitators, each comprising upper and lower web parts with continuous peripheries of substantially circular contour, said agitators being juxtaposed with their periph-

eries separated but inclined toward each other, shafts with which the agitators rotate, pinions on the shafts near their ends remote from the agitators, and means having 5 series of gear teeth respectively meshing with the pinions, said series of gear teeth being relatively close together, and said

shafts being convergent from said agitators to said remote ends adjacent said series of gear teeth, for the purposes set forth.
